UNITED STATES PATENT OFFICE.

PHILIP ALEXANDER, JR., OF CHURCHVILLE, NEW YORK.

TOY BINDING MACHINE.

1,419,096.

Specification of Letters Patent. Patented June 6, 1922.

Application filed April 11, 1921. Serial No. 460,558.

To all whom it may concern:

Be it known that I, PHILIP ALEXANDER, Jr., a citizen of the United States, residing at Churchville, in the county of Monroe and 5 State of New York, have invented certain new and useful Improvements in Toy Binding Machines; and I do declare the following to be a full, clear, and exact description of the invention, such as will enable others 10 skilled in the art to which it appertains to make and use the same.

This invention relates to an improved toy binding machine and one object of the invention is to provide a toy which will represent a grain binder and will have an improved mounting for a beater wheel so that a belt which passes about the shaft of the beater wheel may be held tight and thus rotation of the beater wheel is insured when 20 the toy is rolled along the ground.

Another object of the invention is to so construct the toy that power transmitting means will be provided which will be very simple in construction but very effective in 25 operation.

Another object of the invention is to so construct this machine that power may be transmitted from one of the supporting wheels for the body portion of the machine.

30 Another object of the invention is to provide a toy of the character described which to a great extent will resemble a full size binding machine and will include a representation of a cutter board and conveyer apron.

35 This invention is illustrated in the accompanying drawings, wherein:

Figure 1 is a perspective view of the improved toy.

Figure 2 is a longitudinal sectional view 40 through the toy.

This improved toy binding machine is provided with a body having a horizontal board 1 and converging boards 2 and 3, supporting beams 4, 5 and 6 being placed 45 beneath the board with the supporting beams 4 and 5 at the outer edge portions of the boards 1 and 3 and the supporting beam 6 at the junction of the boards 2 and 3. These beams 4, 5 and 6 will be secured to the 50 boards 1 and 3 and the board 2 will be secured to the beam 6 by nails or other suitable fasteners. A joist 7 is placed at the junction of the boards 1 and 2 and these boards 1 and 2 will be secured to this joist by bolts or other 55 similar fasteners 8 with one of the bolts 8 serving as means for securing a prop 9. A

side board 10 is secured to the outer side edge of the board 1 by fasteners which may pass into the supporting beam 4 and this is provided with an outstanding ledge 11 so that 60 the side board 10 and ledge 11 will resemble the usual cutter boards provided in binding machines. A bracing strip 12 is provided for the boards 2 and 3 and a handle 13 is secured to the inner face of the board 2 just 65 below the bracing strip 12.

In order to movably support the body, there has been provided an axle 14 which extends beneath the board 1 with its outer end portion extending through the supporting beam 4 and out beyond the side board 10, a wheel 15 being rotatably mounted upon the extended end portion of the axle 14. A guard strip 16 is secured to the side board 10 and rear end portion of the supporting beam 4 so that the wheel will be protected when the toy is pushed along the ground. At the inner end of the board 1, the axle is bent upwardly as shown at 17 so that it extends along the inner face of the board 2 for a short distance and is then bent to provide a horizontal section 18 which extends in a higher plane than the portion of the axle beneath the board 1 and has its outer end embedded in the beam 5. Securing strips or brackets 19 are secured to the boards 1 and 2 and engage the axle as shown in Fig. 2 so that the axle will be securely held in place. A supporting wheel 20 which will be termed a driving wheel is mounted upon the elevated portion 18 of the axle and a pulley wheel 21 is also rotatably mounted on this portion of the axle and connected with the wheel 20 so that when the wheel 20 rotates, the pulley will rotate with the wheel. 95

The beater 22 extends above the board 1 and is provided with a shaft 23 which has its outer end portion provided with a pivot pin 24 mounted in an opening formed in the standard 25. The inner end portion of this shaft 23 is enlarged to provide a pulley element 26 and a pin 27 which forms a pivot pin for this end of the shaft for receiving the eye at the lower end of the spring hanger 28. This spring 28 is secured to the board 2 above the opening 29 by means of a suitable fastener 30 and thus the beater will be rotatably mounted and at the same time have its inner end portion yieldably held in a raised position so that when the inner end portion of the beater shaft is brought downwardly against the tension of the spring 28 100 105 110

to permit the belt 31 to be passed about the pulley 21, the spring will tend to draw the inner end portion of the beater shaft upwardly and will thus stretch the belt tight and insure proper transmission of rotary movement from the pulley wheel 21 to the beater. At 32 is shown a representation of a cord-holder with a piece of cord 33 passing from it and extending beneath the board 2 where it will be secured to the inner face of the board.

When this device is in use, it is pushed along the ground and the beater will be rotated above the board 1 which represents the conveyer platform usually provided to the rear of the cutter teeth, which teeth are represented by suitably painting the forward edge portion of the board 1 as shown at 34. Of course, the device will not cut the grass but since the grass will be caused to pass under the board 1, it will appear that cutting has taken place.

I claim:

1. A toy binder comprising a body having an opening, a beater having a shaft rotatably mounted above the body and having one end portion extending above the opening, supporting wheels for said body, a pulley turning with one of said wheels, a belt passing through the openings of said body and about said pulley and beater shaft, and resilient means drawing said beater

shaft away from said pulley to tighten said belt.

2. A toy binder comprising a body having a horizontal board and an upwardly and outwardly inclined board provided with an opening, a standard, a spring hanger carried by the inclined board above the opening, an axle shaft, wheels upon the shaft, one wheel being positioned beneath the inclined board, a pulley upon the axle turning with the last mentioned wheel, a beater having a shaft rotatably mounted by said standard and spring hanger, and a belt passing about the pulley and beater shaft and stretched tight by the action of said spring hanger.

3. A toy comprising a body including a portion provided with an opening, a standard, a spring hanger carried by the body above the opening, supporting wheels for the body, one wheel being positioned beneath the portion of the body having the opening formed therein, a pulley turning with the last mentioned wheel, a beater having a shaft rotatably mounted by said standard and said spring hanger, and a belt passing through the opening and about the pulley and beater shaft and stretched tight by the action of said spring hanger.

In testimony whereof I have hereunto set my hand.

PHILIP ALEXANDER, JR.
